UNITED STATES PATENT OFFICE.

WILLIAM WEAVER, OF CHICAGO, ILLINOIS, ASSIGNOR TO McCORD & COMPANY, OF CHICAGO, ILLINOIS, A CORPORATION OF NEW JERSEY.

APPARATUS FOR MAKING CORES.

SPECIFICATION forming part of Letters Patent No. 743,121, dated November 3, 1903.

Application filed October 23, 1902. Serial No. 128,884. (No model.)

To all whom it may concern:

Be it known that I, WILLIAM WEAVER, a citizen of the United States, residing at Chicago, in the county of Cook and State of Illinois, have invented a certain new and useful Improvement in Apparatus for Making Cores, of which the following is a full, clear, concise, and exact description, reference being had to the accompanying drawings, forming a part of this specification.

My invention relates to apparatus for making cores, and especially to apparatus for making cores used in casting journal-boxes for railway-cars.

Prominent objects of the invention are to provide an apparatus which will permit the simplification of the method of making cores and the reduction of the expense and time required in making the same; to arrange for securing absolute accuracy, uniformity, and symmetry in the finished core; to provide a simple, practical, and effective apparatus for this purpose, and to accomplish the above results in a practical and efficient manner.

In making cores as herein set forth the core is made in a single piece instead of in two or more separable parts, as has been and is now common. By making the core of a single piece it is practically perfect—that is, it is uniform and symmetrical throughout—whereas when made in a plurality of pieces there is great liability of the different pieces being more or less out of register with one another when secured together, with the result that the finished core is imperfect and unsymmetrical.

In making the core in a single piece in accordance with the manner of carrying out my invention herein set forth I provide a hollow structure or box whose interior has the shape or conformation which it is desired the core shall have. This hollow structure or box is made of separable parts which can be readily associated together to make the complete box and easily separated. It also has an open top or other large opening. The core is made by first associating the separable parts of the hollow structure and then filling the same with sand through the open top or other opening and then pounding or compressing the sand in the usual way in mold-

ing processes. The core is thus formed inside of the hollow structure. The separable parts of such structure are then separated and removed, leaving the complete core in a single piece. The separable portions of the hollow structure or box are conveniently provided with locking devices by which they can be locked together after being properly associated to make the complete box. I also provide where necessary removable parts or slides for the box by which different shapes or configurations can be imparted to the core as required in the various individual instances.

In the accompanying drawings I have illustrated a core-box and core made therein adapted for the casting of car-axle boxes for railway-cars and the like. It will be understood, however, that I do not wish to confine myself to this particular form of core-box, as it is obvious that the invention can be applied to other forms or species of cores with equal facility.

In the accompanying drawings, Figure 1 is a perspective view of a core-box for making cores for car-axle boxes in accordance with my invention with certain slides partially removed. Figs. 2 and 3 are respectively a plan and side elevation of the box. Fig. 4 is a longitudinal section taken on line 4-4 in Fig. 2. Fig. 5 is an end elevation. Figs. 6, 7, 8, 9, 10, and 11 are views of different removable parts of the box. Fig. 12 is a side elevation, on a smaller scale, of a core-box with a supplemental core arranged upon it. Figs. 13, 14, and 15 are respectively a side elevation, a plan view, and end elevation of the finished core.

In the drawings I have shown a core-box A adapted to form the core for a car-axle box. To such end its interior has the general configuration the core must have. This box A consists of two separable parts or sections 11, each of which is desirably a longitudinal half of the box made by dividing the same along a central vertical plane. The box is made with an open top and bottom, so that each section or half really comprises only a side wall and the halves of the end walls. These halves are intended to be readily fitted together and to be easily separated from one another, so that at will they can be formed

into a complete structure or divided into the component parts thereof. To such end the sections or halves are provided with dowel-pins 22, Fig. 4, and sockets 33, adapted to receive said pins. In order to hold the two halves or sections firmly and securely together when desired, the same are provided with clamping or locking devices, a convenient arrangement being to provide the ends 10 of the sections or halves with plates 44, having inclined lugs 55, and to provide clamps 66, adapted to fit over the lugs 55. By driving the clamps 66 upon the plates 44 the two sections or halves 11 can be held very securely together.

The halves or sections 11 are made with inwardly-extending projections 77 and inclined surfaces 88, which are respectively opposite one another in the two halves. The 20 sides 11 are also provided with notches or recesses 99 and 1010. The opposite end portions 1111 of the sides 11 are made higher than the intermediate portion. The inner surfaces 1313 of the ends are desirably inclined outwardly. The end surfaces 1414 are desirably inclined so as to flare upwardly.

The sides 11 are provided with interior vertically-arranged guideways 1516 and cross-recesses 1717 1818, and vertically-movable 30 slides 1920, having lateral projections 2121 2222, are adapted to fit and slide in the guideways 1516 and to have their projections 2121 2222 fit in the transverse recesses 1717 1818. The sides 11 are also provided with 35 slots or apertures 2323, and into these slides 2424 are adapted to fit and move. The slides 2424 are desirably provided with lateral projections 2525, adapted to strike against the sides of the box and limit inward movement. The slots 2323 are in alignment with the guideways 1616, whereby the slides 2020 and 2424 are in alignment with one another and in effect form a single piece when all said 40 slides are inserted. The slides 19 and 20 are 45 made arch-shaped, the curved portions 2626 of the arch being circular. The slides 2424 are made with concave circular surfaces 2727, so that when the slide 20 and the slides 2424 are in position all three together provide a 50 circular opening.

The core-box A is also provided with triangular apertures or openings 2828, adapted to receive a triangular slide or rod 29. The rear face of the rod 29 coincides with the 55 edges 8a8a, which mark the terminations of inclined portions 88 of the interior wall of the box, Fig. 4.

A fallow-plate 30 for the core-box to rest upon is provided, Fig. 4, and a pair of brackets or supports 31 and 32 are adapted to fit within the box at its opposite ends and to rest upon the plate 30. The bracket 30 has a flat top portion 33 and a concave inclined top portion 34. The flat top portion 33 fits 60 immediately below the slide-rod 29. The bracket 32 has a concave top or seat 35, Figs. 4 and 5, which meets and forms continua-

tions of the flaring sides 1414 of the box and of the arched edge 26 of the slide 19.

A bracket B is adapted for arrangement 70 upon the top of the box adjacent to the elevated portions 1111 of the box sides, as shown in Figs. 2 and 3. This bracket B is composed of two parts 36 and 37, Figs. 1, 8, 9, 10, and 11, whereof the part 36 is arranged 75 adjacent to the elevated portions 1111 and the part 37 adjacent to the part 36. The part 36 is constructed with straight edges 3838, adapted to fit against the edges of the portions 1111, and also with a projecting portion 39, adapted to fit between said portions 1111, and so prevent movement of the part 36 relatively to the box. Lugs 4040 project rearwardly from the portion 39. The front edge 41 of the part 36 is inclined downwardly 80 and forwardly, as shown in Figs. 1 and 3. The part 37 has downwardly-projecting lugs 4242 4343, whereof the lugs 4242 are adapted to fit into the notches or recesses 1010 on the opposite sides of the box, and the lugs 4343 90 are adapted to project downwardly into the interior of the box. The rear face 44 of the part 37 is inclined upwardly and rearwardly to correspond with the front face of the part 36, whereby the part 37 when placed upon 95 the top of the box and locked in position by having its lugs 4242 enter the notches 1010 will also lock the front end of the part 36. Thus the bracket B, composed of the parts 36 and 37, can be firmly and securely held in 95 position.

In Fig. 12 is shown the box A, with the usual core C for making the lug for the dust-guard applied to it. To such end the box A is provided with a bracket 46, having depending lugs or projections 4747, adapted to fit into the notches 99 in the sides of the box A, so as to hold said bracket firmly in position at the proper place. The inclined wall 48 of the bracket 46 has the same inclination as 110 the rear surface of the core C, whereby the core C when placed in position can be moved against the bracket 46 and there held.

In making the core by means of the arrangement hereinbefore set forth I proceed as follows: The two sides 11 of the core-box are placed together and securely locked against separation by the clamps 66. The box is then placed upon the fallow-plate 30, and the brackets 31 and 32 are put in position within 115 the box, so as to rest upon the plate 30. The slides 2424 and 29 are then placed in position and sand or core mixture is introduced into the box and packed with the hands, so as to fill all the corners. The usual rods to support 120 the cores are then placed in position, and the sand is then packed with a rammer, the box being partially filled. The slides 19 and 20 are then placed in position, and the box is filled with the sand and packed tight and the 125 top smoothed off with a straight edge. The bracket B is then placed in position and driven downwardly until the lugs 4343 and 130 4040 embed themselves in the sand, and the

bracket rests upon the top edges of the box. The bracket 46 is then placed in position and the lug C is set upon the top of the box against the bracket 46. This forms the core 5 complete. By referring to Figs. 13, 14, and 15, showing the complete core D, the effect of the core-box and its removable parts can be seen. The sides of the core-box form the side walls 50 50 of the core, the projections 10 77 on the core-box walls forming the indentations or recesses 51 51 in the core. The inclined portions 8 8 of the core-box form the inclined walls 52 52 of the core. The inclined or bulging end surfaces 13 13 of the core-box 15 form the inclined or wedge-like ends 53 53 of the core. Similarly the flaring walls 14 14 form the flaring surfaces 54 54, the brackets 31 32 the lower walls 55 56, respectively, the slide 19 the recess 57, providing the top of 20 the rear face of the dust-guard slot, the slides 20 and 24 24 the recess 58, which provides the inner dust-guard wall, and the triangular rod 29 the recess 59, which provides the lip on the box. The bracket B, with its lugs 43 43, forms 25 the recesses 60 60 for the wedge-lugs. The supplemental core C forms the lug. After the core is completed the box and its various parts are separated and removed, so as to leave the core standing. The top brackets 30 B and 46 are removed, then the slides 19, 20, 29, and 24 24, and then the clamps 5 6 are removed and the halves 1 1 of the box withdrawn. The core is thus left upon the bottom plate 30 and the brackets 31 and 32. In 35 this condition it is baked, if desired.

The apparatus can be used for making green sand cores—that is, cores which do not require baking. In such case a special iron arbor is provided to support the sand, the 40 arbor being inserted in the core-box and then the slides and brackets put in place, as before. When the core is completed, it can be placed directly into the mold, which is then in condition to receive the hot metal.

45 It will be seen from the foregoing that by employing my invention the core is made in a single piece and is therefore perfect, in contradistinction to a core made of two or more pieces pasted together, with the usual result 50 that pieces are not exactly in register with one another. It will also be seen that the apparatus is simple, cheap, and practical and that the process requires but little time—much less than required in making the core 55 of two pieces and then securing them together. It will also be seen that the core must necessarily be perfect when completed. This is due to the fact that the various core-making elements—that is, the box, slides, brackets, 60 &c.—must necessarily be put in the proper places and cannot be varied or changed from their proper locations. This also insures every core being exactly alike.

It will be understood that I do not wish to 65 confine myself to the exact apparatus herein set forth. Departures can be made from it without departing from the spirit of my in-

vention. The apparatus herein shown for making journal-box cores can be varied and changed and the entire invention can be applied for making entirely different kinds or forms of cores.

What I do claim as my invention, and desire to secure by Letters Patent, is—

1. An apparatus of the class specified, comprising a box having an open top and having its ends split vertically so as to permit horizontal separation of the sides of the box, the interior of the box being formed to give the core the desired configuration, and means for clamping the separable sides of the box temporarily together, substantially as described. 75

2. An apparatus of the class specified, comprising a box having an open top and having its ends split vertically and having its interior formed to produce the core configuration, clamping devices for clamping the split ends of the box temporarily together, and core-modifying devices detachably secured to the box, substantially as described. 85 90

3. In apparatus for making journal-box cores, the combination with a hollow structure or box having its interior formed to produce the configuration of the core, of a bracket 31 for forming the lower surface of one end 95 of the core, and a pin 29 arranged to fit in apertures formed in the sides of the box above the bracket 31, substantially as described.

4. In apparatus for making journal-box cores, the combination with a box having its interior formed to produce the core configuration, of a supplemental core C situated upon the top of the box, and means for holding said core in position on the box, substantially as described. 95 105

5. In apparatus for making journal-box cores, the combination of a box having its interior formed to produce the core configuration, of a bracket 46 adapted to be detachably secured to the top of the box, and a supplemental core C resting upon the box against the bracket 46, substantially as described. 110

6. An apparatus for making journal-box cores, comprising a box open at its top and bottom and having its ends split vertically so as to permit horizontal separation of the sides of the box, means for clamping the sides of the box temporarily together, brackets adapted for arrangement at the bottom of the box to form the upwardly-extending lower end surfaces of the core, and devices for forming the other modifications of the core, adapted to be detachably secured to the box, substantially as described. 115 120

7. A core-making apparatus, comprising a box having an open top and bottom and made in separable parts, clamping devices for temporarily holding the ends of the box together, the said box being provided with interior guideways 15 and 16 and also with slots 23, 23, and apertures 28, 28, and its sides being constructed with notches 9, 9 and 10, 10, slides 19 and 20 adapted to work in the guideways 15 and 16, slides 24, 24, adapted to work 125 130

in the slots 23, 23, said slides 24, 24, being provided with means for limiting their inward movement, a rod 29 adapted to fit into the apertures 28, 28, and brackets or supports 31, 32 adapted to fit within the box at the ends thereof.

8. A core-making apparatus comprising a box having an open top and bottom and made in separable parts, clamping devices for temporarily holding the ends of the box together, the said box being provided with interior guideways 15 and 16 and also with slots 23, 23 and apertures 28, 28, slides 19 and 20 adapted to work in the guideways 15 and 16, slides 24, 24, adapted to work in the slots 23, 23, said slides 24, 24, being provided with means for limiting their inward movement, a rod 29

adapted to fit into the apertures 28, 28; brackets or supports 31, 32 adapted to fit within the box at the ends thereof, a bracket B consisting of parts 36 and 37, the former of which is provided with a projecting portion 39, and lugs 40, 40, and the latter of which is provided with lugs 42, 42 and 43, 43, whereof the former are adapted to fit into the slots 10, 10, and a bracket 46 having lugs 47 adapted to fit in the notches 9, 9, substantially as described.

In witness whereof I hereunto subscribe my name this 13th day of October, A. D. 1902.

WILLIAM WEAVER.
